TRIM FOR A VEHICLE CAB

Harvey F. Dick, Chagrin Falls, Ohio, assignor to White
Motor Corporation, Cleveland, Ohio, a corporation of Ohio

Filed Feb. 23, 1968, Ser. No. 10,691

Term of patent 14 years

Int. Cl. D12—74

U.S. Cl. D14—6

The elements shown in broken lines are only included for illustrative purposes.

I claim:

The ornamental design for a trim for a vehicle cab, as shown and described.
